UNITED STATES PATENT OFFICE

2,454,714

CONVERTER FOR IGNITION SYSTEMS

Joseph T. Osterman, Northampton, Mass., assignor to American Bosch Corporation, Springfield, Mass., a corporation of New York

Application November 9, 1946, Serial No. 709,021

12 Claims. (Cl. 315—57)

1

This invention relates to ignition systems for internal combustion engines and more particularly to a high frequency converter unit for use in an ignition system of an internal combustion engine or the like and adapted to be interposed in such system to convert said system to a high frequency system of the type disclosed in patent to Whisler Number 1,376,846.

An object of the invention is to provide a high frequency converter unit for ignition systems wherein all of the components necessary to convert the system to a high frequency system are in a single unit which is adapted for application to any existing engine.

Another object of the invention is to provide a new and improved high frequency converter for ignition systems which may be easily and quickly interposed in the leads of a high tension system to convert said system to a high frequency system.

Another object of the invention is to provide a relatively simple and economical, yet efficient, high frequency converter for ignition systems.

Another object of the invention is to provide a high frequency converter of the type set forth wherein all of the necessary components to convert a high tension system to a high frequency system are hermetically sealed in a single unit and which may be impregnated with an insulating material after assembly and sealing of the unit.

Another object of the invention is to provide a converter unit of the type set forth which unit is relatively free from expensive soldered connections.

Other objects and advantages of the invention will be apparent from the following description taken in connection with the accompanying drawings. It will be understood that many changes may be made in the details of construction and arrangement of parts without departing from the scope of the invention as expressed in the accompanying claims. I, therefore, do not wish to be limited to the exact details of construction and arrangement of parts shown and described, as the preferred form of the invention has been shown by way of illustration only.

Referring to the drawings:

Fig. 1 is a diagrammatic view of an ignition system embodying the invention; and

Fig. 2 is a sectional view through a high frequency converter constructed according to the present invention.

For the purpose of illustrating the invention, there has been shown diagrammatically in Fig. 1

2

a high frequency ignition system employing a converter such as the present invention. This system, which is of the type generally disclosed in Patent Number 1,376,846 to Whisler comprises the conventional current supply means A from which current passes to the distributor B which is connected by the leads C to each of the cylinders of the engine which are adapted to be ignited by spark plugs D, one of which has been shown by way of illustration. Interposed in the leads C from the distributor B are the converter units E, and the present invention relates primarily to the provision of a new and improved high frequency converter unit adapted to be interposed in the leads of a conventional high tension ignition system to convert said system to a high frequency system having all of the advantages of such high frequency systems as pointed out in the aforementioned Whisler patent.

The converter comprises a condenser F adapted to receive current from the usual current source as shown and described and to discharge through a spark gap G to the inductively coupled primary H and secondary I, which secondary is connected to the spark plug D and adapted to supply high frequency current thereto.

The high frequency converter unit, the details of which are shown in Fig. 2, comprises a metallic casing or housing I containing the conventional type tubular paper and foiled wound condenser 2 which is wound on the arbor formed by the paper tubes 3 and 4 which are joined together by cementing or the like.

Within the tube 3 is positioned the spark gap 35 which comprises the casing 5 of glass or the like and having the metallic end plates 6 and 7 which are secured to opposite ends of the casing 5 and which support the electrodes 8 and 9 respectively.

The terminal 10, adapted to be connected to a harness lead of the ignition system, is formed of a metallic insert in the molded plastic member 11 which also has the insert 12 molded therewith and which is adapted to be secured to the casing I by circumferentially soldering the end 45 13 to the casing I.

The opposite end of the casing I is adapted to be closed by the molded plastic member 14 which has the hollow metallic terminal 15 molded therein and which also has an annular insert 12 having the end 13 adapted to be secured to the casing I by soldering as previously described.

The molded plastic member 14 has the tubular extension 16 adapted to be surrounded by the paper tube spacer 17 and adapted to contain

the arbor 18 for the primary 19. This primary consists of a space-wound single layer winding on the paper tube 18 and is adapted to be connected at its upper end to the terminal 20 which is also connected to the terminal 7 on the spark gap, and at its opposite end is soldered to the clip 21 which, in turn, is soldered to the grounding clip 22 for the primary and which is interposed between the extension 16 on the cap member 14 and the wall of the casing 1 for grounding the primary through said casing.

Within the arbor 18 for the primary is positioned the secondary 23 which is wound on the paper tube having the metal end cap terminals 24 and 25. The end cap 25 is held in contact with the contact member 20 by the coil spring 26 which is interposed between the terminal member 15 and the terminal 24 and which spring is adapted to electrically connect said terminals 24 and 15.

The spring washer 27 is provided for loading the condenser against the terminal plate 28 for the condenser which is spring loaded through the gap and secondary by the spring 26 and which terminal plate 28 is provided with radial slots, not shown, for allowing the passage of impregnating material to the interior of the converter.

Between the condenser and the adjacent wall of the casing 1 is provided the insulating tube 29.

Between the grounding clip 22 for the primary and the adjacent wall of the casing 1 is positioned the end of the condenser grounding strip 30 for grounding the condenser to the casing 1.

The terminal 10 is adapted to be connected to the ignition lead from the distributor and the terminal 15 of the converter is adapted to be connected to the terminal to the spark plug.

Within the tubular arbor for the secondary 23 is positioned the bellows 31 of rubber or other suitable resilient material which functions as a temperature expansion compensator for the oil impregnation with which the interior of the converter is filled through the hollow terminal 10 after the converter has been completely assembled and then the plug 32 is inductively soldered in the end of the hollow opening in the terminal 10 to prevent escape of any of the oil with which the converter is completely filled.

The washer 33 is provided to load the primary 10 arbor or insulator against the terminal 20.

In operation the condenser 2 is charged by the usual current source and said condenser discharges through the spark gap which is connected to the primary and secondary which are inductively coupled and the secondary is connected to the terminal 15 which is adapted to be connected to a lead from the conventional spark plug to supply high frequency current to the spark plug in the usual manner.

From the foregoing it will be seen that I have provided simple, efficient and economical means for obtaining all of the objects and advantages of the invention.

Having described my invention, I claim:

1. In a device of the character described, a tubular casing, molded cap members of insulating material adapted to overlie the opposite ends of said casing, said cap members having inserts forming terminal members for connection to leads of an ignition system, and also having flanged inserts secured to said casing for securing said terminals and cap members in position thereon, spark gap, and a transformer comprising primary and secondary coil members in said

casing for forming a high frequency converter adapted to be interposed in the ignition lead of an internal combustion engine.

2. In a device of the character described, a tubular metallic casing, molded cap members of insulating material, said cap members having inserts forming terminals for connection to leads of an ignition system and supports for supporting said cap members in position on the ends of said casing, one of said cap members having a hollow extension portion in said casing, a spark gap, condenser, a hollow primary and a secondary member in said casing, said secondary member being located within said hollow primary member and said primary member having a portion extending into said hollow extension portion of said cap member for positioning the members in aligned relation with the adjacent terminal member.

3. In a device of the character described, a casing, a spark gap, condenser, primary and secondary members in said casing to form a high frequency converter for ignition systems for internal combustion engines, said primary and secondary members being in telescoping relation, and a bellows within a hollow central portion of said telescoping members, said casing being filled with oil and said bellows being adapted to function as a temperature expansion compensator for said oil.

4. In a device of the character described, a casing, a spark gap, condenser, primary and secondary members in said casing to form a high frequency converter for ignition systems for internal combustion engines, said primary and secondary members being in telescoping relation, and a resilient bellows within a hollow central portion of said telescoping members, said casing being filled with oil and said resilient bellows being adapted to function as a temperature expansion compensator for said oil.

5. In a device of the character described, a tubular metallic casing, molded cap members of insulating material, one adapted to extend over each end of said casing, a terminal member supported by each of said cap members, each of said cap members having a supporting flange secured thereto and secured to said casing adjacent an end thereof for securing said cap members in position over the ends of said casing, and spark gap, condenser and transformer elements in said casing with said spark gap in electrical connection with one of said terminals and said secondary in electrical connection with the other of said terminals and said device forming a high frequency converter for an ignition system for internal combustion engines.

6. In a device of the character described, a casing, said casing having terminals adjacent the opposite ends thereof adapted to be connected to the leads of an ignition system, a spark gap, condenser and transformer elements in said casing whereby to form a high frequency converter for ignition systems, said casing containing a liquid insulating medium, and a temperature expansion compensating element in said casing in said liquid insulating medium.

7. In a device of the character described, a casing, said casing, having terminals adjacent the opposite ends thereof adapted to be connected to the leads of an ignition system, a spark gap, condenser and transformer elements in said casing whereby to form a high frequency converter for ignition systems, said casing containing a liquid insulating medium, and a resilient temperature

expansion compensating element in said casing in said liquid insulating medium.

8. In a device of the character described, a casing, said casing having terminals adjacent the opposite ends thereof adapted to be connected to the leads of an ignition system, a spark gap, condenser and transformer elements in said casing containing a liquid insulating medium, and a temperature expansion compensating element in said casing in said liquid insulating medium, one of said terminals having means whereby said insulating medium may be inserted into said casing.

9. In a device of the character described, a casing, cap members extending over the opposite ends of said casing and each having portions for securing said cap members on said casing, a spark gap and transformer in said casing, a terminal member supported by each of said cap members, one of said terminal members having an opening therethrough and means for closing said opening whereby a liquid insulating medium may be inserted into said casing through said opening after said cap members have been positioned on said casing and means for sealing said opening to prevent escape of said insulating medium.

10. In a device of the character described, a casing, spark gap and transformer members in aligned relation in said casing, a condenser in said casing, terminal members secured adjacent the opposite ends of said casing whereby said unit may be interposed in the leads of an ignition system, said transformer member comprising a hollow primary member, a secondary member in said hollow primary member and a contact spring also in said hollow primary member for loading said secondary member against the adjacent contact of said spark gap and said contact spring electrically connecting said secondary member with the adjacent terminal member.

11. In a device of the character described, a casing, spark gap and transformer members in aligned relation in said casing, a condenser in

said casing, terminal members adapted to be secured adjacent the opposite ends of said casing whereby said unit may be interposed in the leads of an ignition system, said transformer member comprising primary and secondary members in telescoping relation and a contact spring adapted to load said secondary against the contact of said spark gap and to electrically connect said secondary with the adjacent terminal member, said secondary having a hollow portion, a liquid insulating medium in said hollow portion and a temperature expansion compensating bellows therein.

12. In a device of the character described, a casing having openings at its opposite ends, spark gap and transformer members in aligned relation in said casing, a condenser in said casing, cap members closing the opening at the opposite ends of said casing, terminal members secured adjacent the opposite ends of said casing whereby said unit may be interposed in the leads of an ignition system, said transformer member comprising primary and secondary members in telescoping relation and a contact spring within said primary member for loading said secondary against a contact of said spark gap and electrically connecting said secondary with the adjacent terminal member and a resilient clip connected to said primary and interposed between the wall of said casing and a portion of one of said cap members for grounding said primary to said casing.
